UNITED STATES PATENT OFFICE

167,269

TRAY

Melvin A. Mandelko, Fort Dodge, Iowa

Application September 22, 1951, Serial No. 16,712

Term of patent 14 years

(Cl. D44—10)

To all whom it may concern:

Be it known that I, Melvin A. Mandelko, a citizen of the United States, residing at Fort Dodge, in the county of Webster and State of Iowa, have invented a new, original, and ornamental Design for a Tray, of which the following is a specification, reference being had to the accompanying drawing, forming a part thereof.

Fig. 1 is a perspective view of a tray, showing my new design;

Fig. 2 is a front end view;

Fig. 3 is a top plan view; and

Fig. 4 is a side elevational view thereof.

I claim:

The ornamental design for a tray, substantially as shown.

MELVIN A. MANDELKO.
